UNITED STATES PATENT OFFICE.

JOHN J. O'LEARY, OF GLENSIDE, PENNSYLVANIA.

HAT PROTECTOR.

Application filed August 2, 1921. Serial No. 489,246.

To all whom it may concern:

Be it known that I, JOHN J. O'LEARY, a citizen of the United States, and a resident of Glenside, in the county of Montgomery and State of Pennsylvania, have invented new and improved Hat Protectors, of which the following is a full, clear, and exact description.

This invention relates to a garment protector, and has particular reference to a protector or cover for hats.

An object of the invention is to provide a simple, economical and efficient covering or protector for hats or garments whereby they can be very simply and easily stored away in any suitable space to be protected from dust and dirt while not in use.

Another object resides in the provision of a protector which can be made in large numbers, preferably by machinery, at a very low cost so that they can be sold to the public at a correspondingly low figure.

A further object resides in the provision of means whereby the garment is not only efficiently stored within the protector but is also firmly supported within the protector.

A still further object resides in the particular construction and arrangement of parts which are hereinafter described and claimed and shown in the accompanying drawings.

The invention is illustrated in the drawings, of which—

Figure 1 is a front elevation of the device; and

Figure 2 is a vertical section on line 2—2 of Figure 1.

As shown in the drawings, the preferred embodiment of my invention comprises a protector or container which may be made of paper, cloth, rubber or metal, or any other suitable fabric. This container comprises a rear surface 1 of fabric, preferably flat, and a front surface 2 which is flared out from the rear surface to form therebetween a space for the garment, which in this case is shown as a hat 3. The edges of the two sections 1 and 2 are joined together along abutting portions in any suitable manner, but their lower edges are detachable to provide an opening through which the hat may be

inserted. The lower edge of the rear portion can be bent up in the form of a flap 4 provided with any suitable fastening means, such as 5, which is shown as a snap fastener, to adapt it to be engaged with the lower edge 6 of the flared portion 2. It will be understood that when the garment or hat is not within the container it can be collapsed and folded up in any suitable manner to be carried or stored in a small space.

Extending from the upper edge of the container, I provide a tab or reinforcing strip 7 which may be in the form of some extra heavy material, such as cloth or canvas, which is at its outer end provided with a slot or aperture 8, adapting the container to be hung over any suitable support such as a pin or hook 9. It is, of course, understood that this strip 7 can be made integral with the material of the bag or container instead of being constructed separately and of different material.

This tab 7 preferably, although not necessarily, is integrally extended to a point considerably within the container, and the lower end of this integral extension of the tab 7 is provided with a peg or pin 10. As shown in Fig. 2, this pin or peg 10 is firmly connected to the lower end of the tab 7 by means of a rivet or nail 11. Of course, it is understood that any other suitable means for fastening the peg 10 to the tab 7 can be adopted and still be within the scope of my invention. The tab 7 may be connected or fastened to the container at the point where it passes therethrough by any suitable means, such as glue or cement, or by being sewed thereto, although the particular method of fastening is not shown since it does not form an essential part of the invention.

It will, therefore, be observed that I have provided in an integral member means for fastening or hanging the container to a suitable support and means connected thereto within the container for supporting a garment or hat therein. The hat can be readily slipped up within the container and supported by the peg 10, whereupon the lower flap 4 is fastened to close the bag or container, which can then be hung up in a closet or other suitable storage space.

What I claim is:

A container for storing articles, which comprises a baglike body portion having a lower opening, a flap adapted to close said lower opening, said container having a tab fastened therewithin adjacent its upper edge, said tab having a portion extending

upwardly therefrom through the material of the body portion, this projecting end of the tab adapted to be fastened to any suitable support, and means on the tab within the body portion to support an article. 10

JOHN J. O'LEARY.
